(57) **CLAIM**

The ornamental design for a protective cover for an electric bicycle, as shown and described.

DESCRIPTION

FIG. 1 is a front and left side perspective view of a protective cover for an electric bicycle embodying my new design; FIG. 2 is a rear and right side perspective view thereof, as installed on an exemplary bicycle;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line showing of portions of an electric bicycle are for the purposes of illustrating environmental structure and form no part of the claimed design.

1 Claim, 8 Drawing Sheets
